Primary Examiner — Cynthia Ramirez*Assistant Examiner* — Gino Colan(74) *Attorney, Agent, or Firm* — Gardner Groff Greenwald & Villanueva, PC(57) **CLAIM**

The ornamental design for a combined inflation and deflation valve, as shown and described.

DESCRIPTION

FIG. 1 is a top view of the combined inflation and deflation valve of the present design;

FIG. 2 is a top view thereof shown with the cap separated;

FIG. 3 is a side view thereof;

FIG. 4 is another side view thereof shown with the cap separated; and,

FIG. 5 is a bottom view thereof.

The broken lines shown in the figures are included for the purpose of illustrating elements of the combined inflation and deflation valve and form no part of the claimed design.
